CAT PERCH AND EXERCISE POLE

Guy W. Tucker, Littleton, Colo., assignor to
The Rotuc Corporation, Windsor, Colo.

Filed June 22, 1972, Ser. No. 265,189

Term of patent 14 years

Int. Cl. D30—07

U.S. Cl. D30—42

Fig. 1

Fig. 2

Fig. 3

FIG. 1 is a perspective view of a cat perch and exercise pole embodying my ornamental design;

FIG. 2 is a top plan view thereof; and

FIG. 3 is a side elevational view thereof.

The shading on the drawing is intended to indicate carpeting or fabric which is continuous within the boundaries indicated.

I claim:

The ornamental design for a cat perch and exercise pole, substantially, as shown and described.
